DESIGN FOR A CARD BLANK FOR GREETING CARDS, CALLING CARDS, AND THE LIKE

Edwin H. Jenkins, Finesville, N. J.

Application October 16, 1942, Serial No. 108,537

Term of patent 7 years

To all whom it may concern:

Be it known that I, Edwin H. Jenkins, a citizen of the United States and a resident of Finesville, Warren County, New Jersey, have invented a new, original, and ornamental Design for a Card Blank for Greeting Cards, Calling Cards, and the like, of which the following is a specification, reference being had to the accompanying drawing, forming a part thereof, in which:

Figure 1 is a front view of a card blank for greeting cards, calling cards, and the like showing my new design.

I claim:

The ornamental design for a card blank for greeting cards, calling cards, and the like, substantially as shown.

EDWIN H. JENKINS.
